UNITED STATES PATENT OFFICE.

OTTO A. HOKANSON, OF WOODSTOCK, ILLINOIS, ASSIGNOR TO WOODSTOCK TYPEWRITER COMPANY, OF WOODSTOCK, ILLINOIS, A CORPORATION OF ILLINOIS.

RIBBON VIBRATOR FOR TYPEWRITERS.

Application filed August 29, 1921. Serial No. 496,341.

To all whom it may concern:

Be it known that I, OTTO A. HOKANSON, a citizen of the United States, residing at Woodstock, in the county of McHenry and State of Illinois, have invented certain new and useful Improvements in Ribbon Vibrators for Typewriters, of which the following is a specification.

This invention relates to typewriter mechanism and especially to that portion of a typewriter by which the ribbon is moved into and out of position to cover the printing point and is more particularly applicable to typewriters that fold into a compacted position.

The object of the invention is to provide mechanism of the class named which shall be of improved construction and operation.

The invention is exemplified in the combination and arrangement of parts shown in the accompanying drawings and described in the following specification, and it is more particularly pointed out in the appended claims.

25 In the drawings—

Fig. 1 is a vertical sectional view through a typewriter showing one embodiment of the present invention applied thereto, the parts being shown in folded position;

30 Fig. 2 is a fragmentary sectional view of a portion of a typewriter showing the ribbon vibrator in its operating position in side elevation;

35 Fig. 3 is a fragmentary section substantially on line 3—3 of Fig. 2; and

Fig. 4 is a vertical section of a portion of a typewriter showing the ribbon vibrator in front elevation.

In the drawings, the numeral 10 designates the main or base frame of a typewriter having arms 11 pivoted at 12 thereon. The arms 11 carry a platen carriage frame 13 having a platen carriage 14 and platen 15 mounted to slide thereon transversely of the machine. Key levers 16 are pivoted at 17 on the frame 10 and are connected by sub-levers 18 and links 19 to the type bars 20. The type bars 20 are carried by a type bar segment 21 supported by the main frame. 45 Ribbon spools 22 are carried on brackets 23 at each side of the main frame and a ribbon 24 passes over guides 25 and through loops 26 on the ribbon vibrator 27 by which the ribbon is moved to cover and uncover the 55 printing point.

The vibrator 27 is slidably mounted on a supporting frame or bar 28 which is fixed to a rod 29 extending transversely of the machine frame and pivotally mounted therein. The guides 25 are also rigidly fixed to the 60 rod 29. An arm 30 projects rearwardly from the rod 29 and extends through a slot in a bar 31 slidably mounted on the rear of the machine frame 10. The upper end of the bar 31 engages a lug 32 formed on the platen carriage frame 13 when the platen carriage frame is in operating position so that the bar 31 is held downwardly by the platen carriage frame, thus supporting the ribbon vibrator frame 28 in its operating position 65 shown in Fig. 2. When the platen carriage frame is folded to its compacted position shown in Fig. 1 the bar 31 slides upwardly permitting the arm 30 and the rod 29 to rotate in a counterclockwise direction to 70 bring the vibrator frame 28 into folded position shown in that figure.

The ribbon vibrator 27 is provided with a pair of tongues 33 bent over the edges of the frame 28 to guide the vibrator in its movement along the frame and lugs 34 on the frame 28 limit the downward movement of the vibrator to bring the ribbon to rest at a fixed initial position with the printing point uncovered. The lower end of the vibrator 27 is provided with a pivot pin 35 projecting through a slot 36 in a curved arm 37 which extends through a slot in the frame 28. The arm 37 is formed integrally with a bar 39 which extends laterally from a segment plate 40. The plate 40 is pivotally held by a screw 41 on a bracket 42 secured to the rear wall of the main frame 10. An arcuate flange 43 is supported on the segment 40 and is spaced therefrom by connecting supports 44. An arm 45 also pivotally mounted on the screw 41 projects through the slot between the segment 40 and the flange 43 and is provided with a finger-piece 46 at its forward end by which it may be moved vertically relative to the segment 40. 95

As shown best in Fig. 3, a flat spring 47 is supported by the screw 41 and bears against arm 45 and flange 43 to hold the arm 45 against the segment 40. The arm 45 carries a pin 48 to engage a series of depressions 50, 51 and 52 in the segment 40. By moving the finger-piece 46 the arm 45 may be shifted to bring the pin 48 into engagement with any one of the depressions 100 105 110

50, 51 and 52 so as to adjust the arm 45 relative to the segment. Projecting downwardly from the portion of the arm 45 adjacent the screw 41 is a lug 53 carrying a 5 pin 54 in position to be engaged by a contact-piece 55 secured by screws 56 on an arm 57 projecting upwardly from a bar 58. The bar 58 extends transversely of the machine frame and is pivoted between the side walls 10 thereof to oscillate about its longitudinal axis.

A pair of arms 59 project forwardly from the bar 58 and are provided with pin and slot connections 60 with arms 61, the arms 15 61 being pivotally mounted at 62 on the main frame. A universal bar 63 is suspended by links 64 from the arms 61 in position to be engaged by the key levers 16. Each time a key lever is depressed the bar 20 58 will be rocked to move the contact member 55 forwardly causing it to engage the pin 54 and swing the arm 45 upwardly. The upward movement of the arm 45 carries with it the segment 40 by which the 25 slotted arm 37 is carried. This will move the pivot pin 35 upwardly and shift the ribbon vibrator to bring the ribbon over the printing point at the time that the type bar 20 is actuated by the key lever to cause 30 it to strike the platen. When the key lever is released the ribbon vibrator and its actuating parts will be free to move downwardly, thus uncovering the printing point. As shown in the drawings, the downward movement 35 of the vibrator is produced by the action of gravity, but it will be understood that a spring may be employed to assist the force of gravity, if desired.

Where a two-color ribbon is employed it 40 is desirable to lift the ribbon to different heights for writing on either one or the other of the two colors. When the arm 45 is adjusted into position *c*, Fig. 2, with the pin 48 in engagement with the depression 50 45 the ribbon will be raised a maximum amount at each operation of a key lever. If the lower half or zone of the ribbon is colored red this adjustment of the arm 45 will be used for writing on red. When the 50 arm 45 is shifted to position *b* with the pin 48 in contact with the depression 51 the pin 54 will be shifted forwardly a short distance away from the contact member 55 so that the two will move into engagement at 55 a later time in the operation of a key lever and the ribbon will be raised a lesser distance. This adjustment will bring the upper zone of the ribbon over the printing point for writing on black. If the arm 45 is 60 swung to its uppermost position *a* the pin 54 will be shifted out of the path of movement of the contact member 55 and operation of a key lever will not affect the ribbon vibrator. This position may be used for 65 cutting stencils.

The downward movement of the segment 40 is limited by a tail-piece 65 which projects into a slot in the rear wall of the frame 10.

When the arms 11 and the platen carriage frame mounted thereon are swung upwardly and forwardly to their folded position the bar 31 will be released permitting forward tilting of the ribbon vibrator support 28 which will thus be folded out of the path of the platen frame to its full line position shown in Fig. 75

1. During the folding movement of the ribbon vibrator the pin 35 will slide in the slot 36 but will remain in engagement with the slot so that at no time will the vibrator be disconnected from its operating parts. When the platen carriage frame is returned to its operating position the lug 32 will strike the bar 31 and automatically swing the vibrator and its support to its operating position. The movement of the vibrator frame will take place after the platen carriage frame and platen have passed the position to which the vibrator is subsequently moved, thus avoiding any interference on the part of the vibrator with the movement of the platen carriage frame. 85

I claim:—

1. A typewriter having frame parts foldable relative to one another, a ribbon vibrator foldably mounted on one of said parts and normally positioned in the path of folding of the other of said parts, and means controlled by said frame parts for moving said vibrator in operating position when 95 said frame parts are moved into operating position relative to one another. 100

2. In a typewriter, a main frame having a platen carriage frame foldably mounted thereon, a ribbon vibrator foldably mounted on said main frame and normally positioned in the path of folding of said platen carriage frame, and means controlled by said platen carriage frame for restoring said vibrator in operating position when said platen carriage frame is moved into operating 105 position and subsequent to the movement of said platen carriage frame past the normal position of said vibrator. 110

3. In a typewriter, a main frame having a platen carriage frame mounted thereon for movement into and out of operating position, a platen carriage movable along said platen carriage frame, a ribbon vibrator foldably mounted on said main frame, and means actuated by said platen carriage frame when moved into operating position to automatically move said vibrator from 115 folded position to operating position. 120

4. In a typewriter, a main frame, a platen carriage frame mounted thereon for movement into and out of operating position, a platen carriage mounted to travel on said platen carriage frame, a ribbon vibrator foldably mounted on said main frame, and 125 130

- means actuated by said platen carriage frame when moved into operating position to automatically restore said ribbon vibrator to operating position subsequent to the movement of said platen carriage frame past the position occupied by said ribbon vibrator when in operating position.
5. In combination, a typewriter having a main frame a ribbon vibrator support foldably mounted on said main frame below the top thereof, a vibrator slidably mounted on said support, actuating means for said vibrator, and a movable connection between said vibrator and its actuating means above the pivot for said support to permit folding of said vibrator and support to a position within said main frame while maintaining connection with its actuating means.
10. In combination, a typewriter having a ribbon vibrator foldably mounted thereon, a pin on said vibrator, and actuating means for said vibrator having a curved slot engaging said pin and permitting movement of said pin in said slot during folding movement of said vibrator, both ends of said slot being closed to retain said pin therein during folding.
15. In a typewriter, a frame member, a vibrator support pivotally mounted on said frame member, a vibrator slidably mounted on said support, an oscillatory member for actuating said vibrator, and a pin and slot connection between said vibrator and said oscillatory member, the slot for said connection being curved about the pivotal axis of said vibrator support to permit folding of said vibrator support while maintaining connection between said vibrator and said oscillatory member.
20. In a typewriter, a supporting frame, key levers on said frame, a ribbon vibrator foldably mounted on said frame, and means actuated by said key levers for operating said vibrator, said vibrator being slidably, pivotally and non-separably connected with its actuating means to permit folding of said vibrator on said frame.
25. In a typewriter, a main frame, a platen carriage frame foldably mounted on said main frame, a ribbon vibrator support foldably mounted on said main frame, a ribbon vibrator slidably mounted on said support, key levers on said main frame, and means actuated by said key levers for operating said vibrator, said vibrator being movably connected with its operating means at a position between the ends of said vibrator support to permit folding of said vibrator support on said main frame while the continuity of said vibrator with its operating means is unbroken.
30. In a typewriter, a main frame, a platen carriage frame foldably mounted thereon, a ribbon vibrator support foldably mounted on said main frame and having an operative position in the path of folding of said platen carriage frame, a vibrator slidably mounted on said support, key levers on said main frame, means actuated by said key levers for operating said vibrator, and a pin and slot connection between said vibrator and its operating means arranged to permit folding of said vibrator support while maintaining connection between said vibrator and its operating means and means actuated by said platen carriage frame during movement thereof into operating position and subsequent to passing the operating position of said ribbon vibrator for automatically restoring said ribbon vibrator to operating position.
35. In a typewriter, a main frame, a platen carriage frame foldably mounted on said main frame, a ribbon vibrator support foldably mounted on said main frame, a ribbon vibrator slidably mounted on said support, key levers on said main frame, means actuated by said key levers for operating said vibrator, movable means for maintaining connection between said vibrator and its operating means during the folding movement of said vibrator support, and means actuated by said platen carriage frame for automatically restoring said vibrator support to its operating position when said platen carriage frame is moved to operating position.
40. In a typewriter, a main frame, a platen carriage frame foldably mounted on said main frame, a ribbon vibrator support foldably mounted on said main frame, a ribbon

In testimony whereof I have signed my name to this specification on this 27th day of August, A. D. 1921.

OTTO A. HOKANSON.
